UNITED STATES PATENT OFFICE

2,213,229

MACHINE FOR SEPARATING SHOES
FROM LASTSCharles A. Robinson, Salem, Mass., assignor to
United Shoe Machinery Corporation, Borough
of Flemington, N. J., a corporation of New
Jersey

Application July 19, 1938, Serial No. 220,044

9 Claims. (Cl. 12—15.1)

This invention relates to machines for separating shoes from lasts and is herein disclosed as embodied in a treadle-operated machine of the type disclosed in United States Letters Patent No. 2,139,658 granted December 13, 1938 upon the application of Earl A. Besson. The illustrated machine, like that disclosed in the above-mentioned Letters Patent, is provided with a shoe-removing tool mounted upon a carrier which, in turn, is pivotally mounted for heightwise movement upon an arm which is free to swing forwardly and rearwardly with respect to the last. The tool is operated by a rod which is pivotally connected to the carrier and which is urged in a direction having a lengthwise and a heightwise component with respect to the last to cause the shoe-removing tool to move forwardly from an inoperative to an operative position and then to perform a heightwise operative movement against the shoe to raise the rear portion of the shoe from the last. In the machine disclosed in the above-mentioned application the forward component exerted upon the shoe-removing tool depends entirely upon the weight of the moving parts inasmuch as the tool is free to move both heightwise and forwardly.

It is an object of the present invention to provide an improved machine of the type under consideration. In accordance with a feature of the invention there is provided means acting directly upon the swinging arm to urge the arm about its pivotal support in a direction to assist the forward movement of the shoe-removing tool. This additional means thus serves to increase the total forward component acting upon the tool relatively to the heightwise component. This renders it possible to lighten considerably the weight of some of the moving parts of the illustrated machine, for example by making the tool carrier of aluminum rather than of steel, and thereby calls for less effort on the part of the operator in lifting these parts to cause the tool to perform its operative movement of raising the heel portion of the shoe from the last. In the illustrated machine the means under consideration comprises a spring interposed between an operating lever and the swinging arm.

In accordance with a further feature the illustrated machine is provided with positive means for holding the shoe-removing tool against heightwise movement to insure that the tool will move forwardly from an inoperative to an operative position. The illustrated machine is further provided with means operated by the tool upon arrest of the forward movement, for releasing the holding means to enable the tool to perform an operative movement heightwise relatively to the last. This holding means as illustrated comprises a pair of latch members which when engaged are relatively movable lengthwise but not

heightwise of the last to enable the tool to move forwardly while preventing the tool from moving heightwise.

The illustrated machine may be provided with a shoe-separating tool of the type disclosed in the above-mentioned Letters Patent, i. e., a rubber pad which frictionally engages the heel end of the shoe. A tool of this character is desirable in operating upon many types of shoes, particularly in high grade work. The illustrated machine may, however, be provided with a different type of tool, namely a tool which bears forwardly against the rear surface of the last and upwardly against the edge of the heel end of the shoe. This form of tool can be employed without damage upon many varieties of shoes and in certain cases is even preferable to the rubber pad above mentioned.

These and other features of the invention will be described as embodied in the illustrated machine and pointed out in the appended claims.

Referring now to the accompanying drawings, Fig. 1 is a side elevation of the improved machine;

Fig. 2 is a perspective view of the upper portion of the machine;

Fig. 3 is an enlarged showing of the shoe-engaging instrumentalities;

Fig. 4 is a plan view showing the machine as provided with an alternative form of shoe-removing tool;

Fig. 5 is a side elevation illustrating the operation of the machine; and

Fig. 6 is a side elevation illustrating the operation of the machine when provided with the alternative form of shoe-removing tool shown in Fig. 4.

The supporting structure or frame of the machine comprises a base 10 (Fig. 1) from which extends upwardly a column 12 carrying at its upper portion a head 14 secured to the column 12 by a strap-like clamping member 16 and screws 18. A last pin 20 for supporting a last L in inverted position is carried upon the upper end of a slide 22 which is guided for heightwise movement in a guideway formed in the head 14, the last L being within a shoe S. The slide 22 is retained in its guideway by a block 24 (Fig. 3) secured to the head 14 by a screw 26 extending through a vertical slot 25 in the block 24 and 50 through a vertical slot 27 in the slide 22. The block 24 has an inwardly extending tongue 29 which passes through the slot 27 and bears against the bottom of the above-mentioned guideway to space the block 24 to provide running clearance 55 for the slide 22. Formed on the slide 22 are rack teeth 28 which are engaged by a pinion 30 formed upon the end of a spindle 32. A hand wheel 34 (Fig. 2) upon the end of the spindle 32 is provided for enabling the operator to raise and lower the 56

last pin 20 to a desired position of heightwise adjustment. A spring-pressed detent 36 (Fig. 3) holds the slide 22 in adjusted position. A plate 38 secured by a screw 40 to a side of the block 24 has formed in it a slot which engages an annular recess in the toothed portion of the pinion 39 and adjacent to the end of the pinion thereby retaining the pinion and the spindle 32 against axial movement.

10 A shoe-removing tool 42 is secured by screws 44 to a slide 46. The tool 42 consists of a plate of fibre having a flat upper surface 48 and a concave forward surface 50 shaped to engage and to conform approximately to the shape of the heel end of a last. The upper surface 49 adjacent to the edge of the surface 50 is adapted to engage the edge of a shoe upper at the heel end of the shoe to raise the shoe from the last. The slide 46 has a beveled extension 52 for supporting the tool 42, the extension 52 being set back slightly from the surface 50 to clear the last. The slide 46 is retained in a carrier 54 by a cover plate 56, and is free to move forwardly and rearwardly, its forward movement being limited by a pair of stop lugs 58 (Fig. 4) formed on the carrier 54 and its rearward movement being limited by a surface 60 formed on the carrier and engageable with the rear edge 62 of the slide 46. Fulcrumed in the carrier 54 by a pin 64 is a bell crank having a laterally extending arm 66 and a rearwardly extending tail 68. Interposed between the arm 66 and a portion of the carrier 54 is a compression spring 70 which urges the arm 66 against the rear edge 62 of the slide 46 and normally maintains the slide 46 in its forward limiting position. The slide 46 is free also for limited lateral movement and is centered laterally by a pair of spring-pressed plungers 72 mounted in opposite sides of the carrier 54 and engaging the opposite sides of the slide 46.

The carrier 54, which may be of aluminum to lighten its weight, is U-shaped, having a pair of forwardly extending arms 74 the forward ends of which are pivotally connected by pins 76 to a pair of parallel L-shaped arms 78. The lower ends of the arms 78 are secured upon a pin 80 which is journaled for pivotal movement of the arms 78 in bearings 82 formed in a lower portion of the head 14. Secured upon the pin 80 is a bracket 84 (Fig. 2) an upwardly extending portion 86 of which is secured by screws 88 to the arms 78, binding the arms together in a unitary structure. Threaded through the portion 86 is a stop screw 90 which is engageable with a flange 92 (Fig. 1) formed on a bracket 93 secured to the head 14 to limit the rearward movement of the arms 78. Threaded through a downwardly extending portion 94 of the bracket 84 is a stop screw 96 which is engageable with a flange 98 formed on the bracket 93 to limit forward swinging movement of the arms 78.

Fulcrumed upon a pair of pins 100 in a downwardly extending portion of the head 14 is a yoke-shaped lever 102 the forward end of which is connected by a link 104 to a treadle 106 which is fulcrumed in the base 10. A turnbuckle 105 in the link 104 enables the length of the link to be adjusted. The lever 102 has a pair of parallel upwardly inclined rearward extensions 108 in each of which is formed a series of holes 110 for receiving a pin 112 which pivotally connects the lower end of a rod 114 to the extension 108. The rods 114 are pivotally connected at their upper ends to the arms 74 respectively of the carrier 54. A tension spring 116 secured to the

rear portion of the lever 102 and anchored in the base 10 maintains the treadle 106 in its uppermost position and holds the arms 78 rearwardly. It will be observed that the rods 114 extend upwardly and forwardly from the extensions 108 to the arms 74. This inclination may be varied by changing the pins 102 in the holes 110.

One of the pins 112 is diametrically bored to receive a rod 118 the upper end of which is pivotally secured to one of the arms 78. The rod 118 slides freely through the pin 112, the thrust which it exerts upon the arm 78 being yieldingly transmitted through a compression spring 119 which surrounds the lower portion of the rod 118 and which is interposed between the pin 112 and a collar 120 secured to the rod 118.

The carrier 54 is provided with a bearing member 122 which normally supports the rear portion of the carrier 54 by resting upon a support 20 comprising a table 126 upon which is secured a leather pad 128 for cushioning a fibre bearing plate 130. The bearing member 122 extends laterally and is secured to the carrier 54 by bolts positioned beyond the lateral edges of the table 126. The bearing member 122 normally engages the plate 130, and the table 126 is yieldingly supported by a compression spring 132 (Fig. 5) housed in a socket formed in a downwardly extending stem 134 of the table. The stem 134 is 30 guided for heightwise movement in a bracket 136 which is secured to the head 14. A shoulder screw 138 extending through an opening in the table 126 limits heightwise movement of the table 35 and prevents the table from turning about the axis of the stem 134.

A latch 140 (Fig. 3) having an inclined surface 141 and an under surface 142 which is slidably engageable with the upper surface of the tail 68 is guided for heightwise movement in a guideway 143 formed in a block 144. A clamping screw 146 secures the latch 140 to the block 144 in any desired position of heightwise adjustment. The block 144 is slidably mounted for lateral adjustment in a guideway 148 formed in the bracket 45 136. A clamping screw 150 secures the block 144 in any desired position of lateral adjustment.

Secured upon each of the forwardly extending arms 74 is a plate 152 having several grooves. In a boss 153 in each of the L-shaped arms 78 is mounted a spring-pressed plunger which, when the carrier 54 is raised to a sufficient height, will engage in one of the above mentioned grooves and temporarily support the carrier 54 for a purpose later to be explained.

In the operation of the machine as so far described the last L with the shoe S thereon is mounted in inverted position upon the last pin 20 and the treadle 106 is depressed by the operator. The upward thrust of the rods 114 tends to force the carrier 54 both forwardly and upwardly. Upward movement of the carrier, however, is prevented by the tail 68 which is in engagement with the latch 140. The carrier therefore is constrained to move forwardly, which it is enabled to do by reason of the fact that the arms 78 are free to swing forwardly about the pin 80. This forward movement is assisted by the rod 118 which under the influence of the spring 119 yieldingly urges the arms 78 forward. It will be noted that the rod 118 transmits its thrust directly into one of the arms 78 and therefore avoids an excessive upward thrust in the carrier which might cause excessive friction between the tail 68 and the latch 140. The relation between 75

the forward and heightwise components of thrust exerted upon the carrier may be varied by shifting the pin 112 from one to another of the holes 110, the forward component being increased relatively when the pin 112 is shifted rearwardly and being diminished relatively when the pin is shifted forwardly. The carrier continues to move forwardly until the concave surface 50 of the shoe-removing tool 42 comes into engagement with the heel end of the last L. Forward movement of the slide 46 is thereby arrested but the carrier continues to move forward a slight distance until the surface 50 comes into engagement with the rear edge 62 of the slide 46. This relative movement between the carrier and the slide rocks the arm 66 and the tail 68 in a counterclockwise direction, as viewed in Fig. 4, thereby releasing the tail 68 from the latch 140 and enabling the carrier to rise. Continued depression of the treadle will cause the shoe-removing tool 42 acting against the edge of the heel portion of the shoe upper to raise the rear portion of the shoe relatively to the last. The effort of the operator is expended chiefly in overcoming the resistance of the shoe, only a slight additional pressure being required to raise the lightweight aluminum carrier previously mentioned. The operator will ordinarily assist the movement of the shoe in the case of a hinged last by bearing down upon the bottom of the forepart of the shoe with his right hand to break the last. He may at the same time grasp the heel end of the shoe with his left hand and assist the shoe-removing tool in raising the heel end of the shoe. As soon as the heel end of the shoe has cleared the last the shoe may easily be removed by hand and the last may be removed from the last pin. While a stop may be provided for the downward movement of its treadle, it is usually convenient to let the treadle hit the floor. The turnbuckle 135 may be adjusted to give the desired extent of movement of the carrier 54. Upon release of the treadle the various parts will return to their initial positions. It may be noted that in its return movement the tail 68 will engage the inclined surface 141 of the latch 140 until it reaches the undercut surface 142, whereupon it will snap into latching position.

In the modified form of shoe-removing tool shown in Figs. 4 and 6, the tool consists of a U-shaped rubber pad 158 secured to the slide 46 and extending forwardly beyond the forward edge of the slide. The pad 158 is vulcanized upon a metal core 160 which, in turn, is secured to the slide. The pad 158 yieldingly and frictionally engages the heel end of the shoe upper. It will be observed that depression of the treadle causes the forward but not the heightwise component of thrust of the rod 110 to be transmitted to the tool 158. Both components from the rods 110 are transmitted, however, because of the direct connection of the rods 114 to the carrier 54. The total forward component acting upon the tool 158 is therefore relatively great, and is sufficient in relation to the heightwise component to prevent the tool from slipping on the shoe. The exact relation between the two components may be varied, as has already been explained, by shifting the pins 112 in the holes 110. When the machine is provided with a shoe-removing tool in the form of a rubber pad, such as the pad 158, it is important to arrange the pins 112 so as to obtain just enough but not much more than enough forward pressure to prevent slipping and to insure a frictional grip upon the shoe

The friction of the shoe against the last will then be at a minimum and the heel end of the shoe may be raised without excessive effort.

The operation of the machine when provided with this form of shoe-removing tool is substantially the same as above described excepting that the tool 158, after the rear portion of the shoe has been raised from the last, may be further employed to push the shoe forwardly with respect to the last. The forward component of thrust in the rods 114 and in the rod 118 will cause this additional forward movement to take place automatically as soon as the rear portion of the shoe has cleared the last. In case the operator should not remove the last from the last pin before releasing the treadle, it is desirable to have the shoe-removing tool clear the last in its return movement. This is insured by the latching of the spring-pressed detent 156 which temporarily supports the carrier until the last has been cleared. The sudden arrest of the arms 78 in their rearward movement by reason of the engagement of the stop screw 90 with the flange 92 will unlatch the detent and enable the carrier to fall into its initial position. The spring 132 will absorb the shock of the carrier as the bearing member 122 comes into engagement with the fibre plate 130.

Having thus described my invention, what I claim as new and desire to secure by Letters Patent of the United States is:

1. A machine for separating shoes from lasts, comprising a support for a last with a shoe thereon, a shoe-removing tool constructed and arranged to move the rear portion of the shoe heightwise relatively to the last, a carrier for said shoe-removing tool, an arm upon which said carrier is pivotally mounted, a pivotal support for said arm, a rod pivotally connected to said carrier, means for urging said rod in a direction having a lengthwise and a heightwise component with respect to the last to cause the shoe-removing tool to move forwardly from an inoperative to an operative position and then to perform a heightwise operative movement against the shoe to raise the rear portion of the shoe from the last, and means acting directly upon said arm to urge the arm about said pivotal support in a direction to assist the forward movement of said tool.

2. A machine for separating shoes from lasts, comprising a support for a last with a shoe thereon, a shoe-removing tool constructed and arranged to move the rear portion of the shoe heightwise relatively to the last, a carrier for said shoe-removing tool, an arm upon which said carrier is pivotally mounted, a pivotal support for said arm, an operating lever, a rod extending forwardly and heightwise with respect to said last, said rod being pivotally connected at its lower end to said operating lever and at its upper end to said carrier, means for swinging said operating lever in a direction to transmit through said rod a thrust urging said carrier to move forwardly from an inoperative to an operative position and heightwise to cause the tool to raise the rear portion of the shoe from the last, and a spring interposed between said operating lever and said arm to urge the arm about said pivotal support in a direction to assist the forward movement of said carrier.

3. A machine for separating shoes from lasts, comprising a support for a last with a shoe thereon, a shoe-removing tool constructed and arranged to move the rear portion of the shoe

- heightwise relatively to the last, a carrier for said shoe-removing tool, an arm upon which said carrier is pivotally mounted for heightwise swinging movement of said tool relatively to the last, a pivotal support upon which said arm is mounted for forward swinging movement of said carrier relatively to the last, an operating lever, a positive connection for transmitting from said lever to said carrier a force having a component directed forwardly relatively to the last to urge the carrier forwardly from an inoperative to an operative position while said arm swings forwardly about said pivotal support, said force having also a component directed heightwise relatively to the last to urge the carrier heightwise about the pivotal connection of the carrier to said arm while said tool is in operative engagement with the heel end of the shoe to raise the rear portion of the shoe from the last, and a yielding connection for transmitting from said operating lever to said arm a force urging the arm forwardly about said pivotal support to assist in moving the carrier forwardly to bring the tool into operating position.
4. A machine for separating shoes from lasts, comprising a support for a last with a shoe thereon, a shoe-removing tool constructed and arranged to move the rear portion of the shoe heightwise relatively to the last, means for exerting upon said shoe-removing tool a force having components directed forwardly and heightwise relatively to the last, means for holding said tool positively against heightwise movement to insure that said tool will move forwardly from an inoperative to an operative position under the influence of said force, and means operated by said tool upon arrest of the forward movement of said tool for releasing said holding means to enable said tool to perform an operative movement heightwise relatively to the last.
5. A machine for separating shoes from lasts, comprising a support for a last with a shoe thereon, a shoe-removing tool constructed and arranged to move the rear portion of the shoe heightwise relatively to the last, means for exerting upon said shoe-removing tool a force having components directed forwardly and heightwise relatively to the last, a relatively stationary latch member, a latch member connected to said shoe-removing tool for movement therewith, said latch members when engaged being relatively movable lengthwise but not heightwise of the last to enable said tool to move forwardly from an inoperative to an operative position under the influence of said force while preventing said tool from moving heightwise, and means operated by said tool upon arrest of the forward movement of said tool for disengaging said latch members to release said tool to a heightwise operative movement under the influence of said force.
6. A machine for separating shoes from lasts, comprising a support for a last with a shoe thereon, a shoe-removing tool constructed and arranged to move the rear portion of the shoe heightwise relatively to the last, a carrier in which said tool is mounted for limited forward and rearward movement relatively to the last, means for exerting upon said carrier a force having components directed forwardly and heightwise relatively to the last, a relatively stationary latch member, a latch member mounted upon said carrier for movement therewith, said latch members when engaged being

relatively movable lengthwise but not heightwise of the last to enable said carrier to move forwardly from an inoperative to an operative position under the influence of said force while preventing said carrier from moving heightwise, and means operated by said tool upon arrest of the forward movement of said tool for disengaging said latch members to release said carrier to a heightwise operative movement under the influence of said force. 10

7. A machine for separating shoes from lasts, comprising a support for a last with a shoe thereon, a shoe-removing tool constructed and arranged to move the rear portion of the shoe heightwise relatively to the last, a carrier in which said tool is mounted for limited forward and rearward movement relatively to the last, a spring urging said tool forwardly in relation to said carrier, means for exerting upon said carrier a force having components directed forwardly and heightwise relatively to the last, a relatively stationary latch member, a bell crank fulcrumed on said carrier and having a rearwardly extending arm engageable with said latch member to prevent heightwise movement of the carrier while leaving the carrier free to move forwardly from an inoperative to an operative position under the influence of said force, said bell crank having also a laterally extending arm which upon arrest of the forward movement of said tool is rocked by said tool to disengage said rearwardly extending arm from said latch member and thereby to release said carrier to a heightwise operative movement under the influence of said force. 25

8. A machine for separating shoes from lasts, comprising a support for a last with a shoe thereon, a shoe-removing tool constructed and arranged for engagement with the heel end of the last and with the edge of the upper at the heel end of the shoe, means for exerting upon said shoe-removing tool a force having components directed forwardly and heightwise relatively to the last, means for holding said tool against heightwise movement to insure that said tool will move forwardly from an inoperative to an operative position under the influence of said force, and means operated by said tool upon the arrest of the forward movement of the tool by engagement with the last for releasing said holding means to enable said tool to move heightwise against the edge of the upper at the heel end of the shoe to move the rear portion of the shoe heightwise relatively to the last. 40

9. A machine for separating shoes from lasts comprising a support for a last with a shoe thereon, a shoe-removing tool constructed and arranged for frictional engagement with the upper at the heel end of the shoe, means for exerting upon said shoe-removing tool a force having components directed forwardly and heightwise relatively to the last, means for holding said tool against heightwise movement to insure that said tool will move forwardly from an inoperative to an operative position in frictional engagement with the shoe under the influence of said force, and means operated by said tool upon the arrest of the forward movement of the tool by engagement with the shoe for releasing said holding means to enable said tool to move heightwise in frictional engagement with the shoe to move the rear portion of the shoe heightwise relatively to the last. 55

CHARLES A. ROBINSON. 70
